UNITED STATES PATENT OFFICE.

MARTIN RALPH, OF QUEENS, NEW YORK.

COMBINATION-TICKET.

SPECIFICATION forming part of Letters Patent No. 487,540, dated December 6, 1892.

Application filed August 1, 1892. Serial No. 441,837. (No model.)

To all whom it may concern:

Be it known that I, MARTIN RALPH, of Queens, in the county of Queens and State of New York, have invented a new and Improved Combination-Ticket, of which the following is a full, clear, and exact description.

My invention relates to improvements in tickets or tags such as are usually made of paper or card-board and may be made of these or any desired material or combination of materials and are used for price tickets or tags, ornamental and embossed tickets, railway coupon-tickets, or for any purpose whatever.

15 The object of my invention is to produce a simple and cheap ticket which may be very conveniently used and which may be cheaply and rapidly printed or marked and to avoid the loss of time necessary to cut apart when printed together.

To this end my invention consists in a combination - ticket, the construction of which will be hereinafter described and claimed.

Reference is to be had to the accompanying drawings, forming a part of this specification, in which similar figures of reference indicate corresponding parts in all the views.

Figure 1 is a perspective view of a strip of pin-tickets embodying my invention and in position upon a marking-board. Fig. 2 is a cross-section of the same. Fig. 3 is an enlarged transverse section of a strip of pin-tickets. Fig. 4 is a perspective view of a strip of string tickets or tags constructed in accordance with my invention. Fig. 5 is a perspective view of a series of railway coupon-tickets also showing my improvement. Fig. 6 shows a series of connected price-tickets, gummed or not gummed, as may be desired; and Fig. 7 is a broken perspective view of another modified form of ticket in which the central web is narrower than the ticket-strips.

The ticket embodying my invention comprises a central continuous web of any width desired of some material which is sufficiently strong to hold the tickets together, but which may be torn asunder easily when necessary.

As shown in Figs. 1 to 3, a series of pin-tickets is illustrated, these comprising opposite and separate side pieces 10 and 11, which

are exactly similar and are pasted or otherwise secured to a central continuous web 12. The web or strip 12 is of the same width as the tickets, and where the tickets are round-cornered, as shown in the figures referred to, the web is shaped to correspond to the shape of the ticket, although the web may be made narrower than the ticket, as shown in Fig. 7. Here the faces 10^a and 11^a of the ticket, which may be of any shape desired, are fastened to a central narrow web 12^c, which may be easily torn when necessary. The several tickets are separated on opposite sides of the web, as shown at 11^a, and the web thus holds a series of tickets together, so that when one ticket is to be separated from the strip it is simply necessary to tear off the web at a point opposite the inner edge of the ticket where it is joined to the next ticket by the central web. These pin-tickets are provided with pins 13 of the common form, although any kind of pin may be used, and the pins shown have parallel prongs 14, which are adapted to be pushed into any material to which the ticket is to be fastened.

The tickets, it will be understood, may be provided with any desired printed matter and be cut or punched in any variety of manner. These tickets usually have prices or other matter marked on them by hand, and to facilitate this operation a board 16 is employed, which has grooves 15, adapted to receive the prongs 14 of the ticket-pins, and this will enable the tickets to lie upon the board, so that they may easily be marked. It will be seen that a single groove wide enough to receive both prongs of the pins may be used, if desired.

In Fig. 4 I have shown the ordinary string-tickets, which are provided with strings 17, but are separated, as shown at 11^a, in the manner already described, the opposite sides 10^a and 11^b of the tickets being secured to a continuous web 12, as in the case of the pin-tickets.

Fig. 5 illustrates a series of connected coupons or railway-tickets, these being of the usual shape, and they are also constructed as described above, having their opposite faces 10^a and 11^c secured to a continuous web.

Fig. 6 illustrates the common form of price-

ticket constructed in accordance with my invention, each ticket having its opposite faces 10^a and 11^a pasted to a continuous web 12, and these tickets are preferably provided 5 with beveled corners 18.

The examples given serve to illustrate that an endless variety of tickets may be constructed in accordance with my invention, and it will be understood, also, that the tickets 10 may be embossed or ornamented, if desired, like the tickets given as prizes in Sunday-schools and the like, or any desired size of card may be joined in the same manner.

The several tickets may be printed alike 15 on both sides or unlike, as desired, and while the tickets may be separately printed and then pasted to the web in any manner desired I prefer the plan of preparing the stock by cutting the opposite side of the sheet simultaneously by passing both through the 20 same pair of cutters and then attaching the face and back of the sheet of card-board thus prepared by slitting to the desired width to the central web and then printing and cutting, punching, or embossing afterward, as 25 may be found most convenient. In this way

the tickets may be very cheaply printed, and for convenience the strips may be rolled up and the tickets torn off as used.

Having thus fully described my invention, 30 I claim as new and desire to secure by Letters Patent—

1. The combination, with a series of tickets, of a continuous strip extending through all of the tickets between their front and rear 35 faces, secured thereto and severable at the meeting edges of the said tickets, substantially as set forth.

2. As an improved article of manufacture, a ticket-strip consisting in a series of tickets 40 separated at their meeting edges and each formed of two sections, and a continuous strip extending through the series of tickets between their two sections and to which the adjacent faces of said ticket-sections are secured, the strip being severable at the meeting edges of the tickets to provide for their 45 ready detachment, substantially as set forth.

MARTIN RALPH.
